UNITED STATES PATENT OFFICE.

LEWIS A. BALL, OF PAWHUSKA, OKLAHOMA TERRITORY.

RAIL-JOINT.

No. 829,052.

Specification of Letters Patent.

Patented Aug. 21, 1906.

Application filed April 23, 1906. Serial No. 313,298.

To all whom it may concern:

Be it known that I, LEWIS A. BALL, a citizen of the United States, residing at Pawhuska, Osage Indian Reservation, Oklahoma Territory, have invented certain new and useful Improvements in Rail-Joints, of which the following is a specification.

This invention embodies improved means for connecting the meeting ends of rails or similar parts and includes special nut-locking means for the fastenings forming a part of the rail-joint structure.

For a full understanding of the invention and the merits thereof and also to acquire a knowledge of the details of construction of the means for effecting the result reference is to be had to the following description and accompanying drawings, in which—

Figure 1 is a perspective view of a rail-joint embodying the invention, square-headed spikes being shown for attaching the rail-chair, angle-bars, and rails to the ties, said spikes coacting to form a part of the nut-locking mechanism. Fig. 2 is a vertical section bringing out more clearly the arrangement of the parts shown in Fig. 1. Fig. 3 is a vertical sectional view bringing out clearly the formation of the rail-chair and the disposition thereof when bolts are utilized for fastening the same to the rails.

Corresponding and like parts are referred to in the following description and indicated in all the views of the drawings by the same reference characters.

Referring to the drawings, the numeral 1 designates the rails, the numeral 2 angle-bars at opposite sides of the rails, and the numeral 3 a substantial rail-chair which embraces the basal portions of the rails and angle-bars, as shown most clearly in Figs. 2 and 3 of the drawings. The angle-bars 2 are of the common type employed on rails such as are now generally in use and are attached to the rails by means of bolts or similar fastenings 4, passing transversely through these parts in the customary way. The rail-chair 3 consists of a base on which the basal portions of the rails 1 rest, said base being formed with upwardly-extending integral wings at its longitudinal edges, the wings overlapping the base portions of the angle-bars 2 and terminating a short distance below the heads and nuts of the bolts 4.

The arrangement and construction of the chair 3 is such that the nuts and head por-

tions of the bolts 4 are not permitted to turn after said chair 3 is placed in position. As shown in Figs. 1 and 2, the chair 3 is nearly as long as the angle-bars 2, and the base of said chair rests on spaced ties of the road-bed. The vertical fastenings employed to secure the chair, angle-bars, and rails to the ties comprise spikes 5, as shown in Figs. 1 and 2, said spikes passing through vertical openings in the lower portions of the angle-bars, the base portions of the rails, and the wings and base portion of the chair. The spikes 5 of course enter the ties and not only position the joint with reference thereto, but attach the parts of the joint together. The spikes 5 are preferably provided with square heads, and the nut-locking means used consists of a longitudinal key 6, which is adapted to be adjusted longitudinally in such a way as to assume a position in which it abuts with the under sides of the heads or nuts of the bolts 4 and with the inner sides of the heads of the spikes 5. In other words, the vertical arrangement of the members 5 is such that they are adapted to hold the key 6 from outward displacement after said key has been forced between the heads of the spikes 5 and the nuts or heads of the fastenings 4. Two keys are preferably employed, one at each of opposite sides of rails, one of the keys coöperating with the heads of the fastenings 4 and the other of said keys coacting with the nuts of the fastenings 4. The keys may be bent at the ends thereof to prevent longitudinal displacement.

Fig. 3 illustrates a construction in which the chair 3 is of substantially the same form as shown in Fig. 1, except that it will be shorter, so as to occupy a position between the adjacent sides of spaced ties. In this construction the vertical fastenings 5^a, by which the angle-bars and rails are attached to the chair, consist of bolts, the upper ends of which have the usual nuts applied thereto, said bolts being of course arranged between the ties to admit of ready access thereto. Spikes 5^b are employed to secure the rails and angle-bars to the ties, and said spikes engage the edge portions of the angle-bars and basal portion of the rails in the customary way. The fastenings 5^b when driven into the ties will crowd the angle-bars in place in an obvious way. The chair 3 reinforces the joint means in the customary manner.

It will be seen from the foregoing that the

invention is applicable to rail-joints and rails at present in use, or it may be readily adapted for new rails.

In Fig. 3 the nuts at the upper ends of the bolts 5^a will engage the keys 6, and the latter will thus coöperate to prevent unscrewing of the nuts from said bolts 5^a.

Having thus described the invention, what is claimed as new is—

- 10 1. In a rail-joint, the combination of rails, angle-bars at opposite sides of the rails, transverse bolts passing through the angle-bars and rails and connecting said parts together, a rail-chair receiving the basal portions of the rails and the base portions of the angle-bars, 30 the upper edge portions of the chair terminating below the heads and nuts of the bolts which pass through the angle-bars and rails, longitudinal keys interposed between the upper portions of the rail-chair and the heads 35 and nuts of the bolts aforesaid and preventing turning of either the heads or nuts, and vertical fastenings passing through the upper and lower portions of the chair and the basal portions of the angle-bars and rails, and engaging the keys aforesaid to prevent displacement thereof from the positions described.
- 15 2. In a rail-joint, the combination of rails, 40 the upper edge portions of the chair terminating below the heads and nuts of the bolts which pass through the angle-bars and rails, longitudinal keys interposed between the upper portions of the rail-chair and the heads and nuts of the bolts aforesaid and preventing turning of either the heads or nuts, and means for preventing displacement of the keys from the position above described.
- 20 25 2. In a rail-joint, the combination of rails,

angle-bars at opposite sides of the rails, transverse bolts passing through the angle-bars and rails and connecting said parts together, a rail-chair receiving the basal portions of the rails and the base portions of the angle-bars, 30 the upper edge portions of the chair terminating below the heads and nuts of the bolts which pass through the angle-bars and rails, longitudinal keys interposed between the upper portions of the rail-chair and the heads 35 and nuts of the bolts aforesaid and preventing turning of either the heads or nuts, and vertical fastenings passing through the upper and lower portions of the chair and the basal portions of the angle-bars and rails, and engaging the keys aforesaid to prevent displacement thereof from the positions described.

In testimony whereof I affix my signature in presence of two witnesses.

LEWIS A. BALL. [L. s.]
